SAFETY CLASP

Charles A. Domler, Providence, R. I., assignor to
 The Hadley Company, Inc., Providence, R. I.,
 a corporation of Rhode Island

Application February 26, 1943, Serial No 477,250

7 Claims. (Cl. 24—241)

This invention relates to safety clasps such as are used in wrist watch bracelets, necklaces, etc., and its principal object is to provide a clasp which is of simple design and of pleasing appearance, which is quick acting and reliable in operation, and which embodies inner and outer catches designed so that both members must be released before the associated coupling member may be disengaged, but upon closing the outer catch, the inner catch automatically operates to lock the parts.

Further objects relate to various features of construction and will be apparent from a consideration of the following description and accompanying drawing, wherein

Fig. 1 is a top plan view of a part of a wrist watch bracelet having a clasp constructed in accordance with the present invention;

Fig. 2 is an enlarged side elevation of the clasp and associated coupling member;

Fig. 3 is a view similar to Fig. 2 but showing both catches in open or released position;

Fig. 4 is a view similar to Fig. 2 but illustrating the automatic operation of the inner catch in response to closing movement of the outer catch; and

Fig. 5 is an enlarged longitudinal section through the clasp.

The embodiment herein shown comprises a clasp 1 integral with a coupling member 2 secured in any suitable manner to one end of a bracelet B, and a coupling member 3 secured to the other end of the bracelet and having a loop 4 by means of which it may be detachably secured to the clasp 1.

The clasp 1 comprises a substantially hollow fixed body member having a top wall 5 (Fig. 5) formed with an opening 6 spaced from its outer end, and side walls 8 and 9 which diverge beyond the body of the clasp and merge with the coupling member 2. The lower edges of the side walls 8 and 9 are bent inwardly to provide flanges which constitute a bottom wall 10 (Fig. 5), and, together with the side and top walls, provide an elongate chamber which telescopically receives a slideable member 12 formed with an end wall 14, side walls 15 and 16, and a bottom wall 17, more clearly as shown in Fig. 5.

The outer ends of side walls 15 and 16 are provided with upstanding ears 18 which carry a pin 20 for pivotally supporting the outer catch or locking lever 21, and on the inner side of the ears 18 the side walls are formed with aligned recesses 22 adapted to receive the loop 4 of the coupling 3, as illustrated in Fig. 3. It will be

noted that with this construction and arrangement the slideable member 12 and pivotally supported catch 21 are movable together inwardly and outwardly relative to the fixed member.

5 A nose or the like member 25 is secured to the top wall 5 of the fixed member by means of pins 26 and 27, the latter extending downwardly through a suitable slot in the slideable member into the bottom wall 10. The outer end portion 10 of the nose 25 is formed with a cam-like surface 30 which is downwardly inclined toward the recess 22, as illustrated in Fig. 5, and the construction and arrangement of parts are such that the outer end of the nose overhangs and hence blocks 15 the entrance to the recess when the slideable member 12 is at its innermost position (Figs. 2 and 5); but when the slideable member is pulled outwardly to its outermost position (Fig. 3) the recess 22 and end portion of the nose are relatively 20 offset so that the latter no longer obstructs the entrance to the recess and hence the loop 4 may be removed from and inserted in the recess 22.

The slideable member 12 is normally held at its 25 innermost or locking position by a small compression spring 32, one end of which acts against the end wall 14 of the slideable member and the other end against the pin 27, as shown in Fig. 5. When the slideable member 12 is held in its outermost position, as illustrated in Fig. 3, the spring 32 is compressed, and upon the release of the holding force it acts to slide the member 12 to its innermost position, as shown in Fig. 2.

The inner edges of the ears 18 are inclined 35 downwardly and inwardly, as indicated at 35, to cooperate with the inclined surface 30 of nose 25 so as to define a V-shaped recess in which the loop 4 of the coupling member 3 may be inserted, as shown in Fig. 4. The pivoted catch 21 is 40 formed with depending side walls 36, the lower edges of which are engageable with the loop 4 when the catch is swung toward closed or locking position, and hence acts through the loop 4 against the surface 30 of the nose 25 and the edges 35 of ears 18 to cause the slideable member 12 to move outwardly, and upon further closing movement of the catch 21, its side walls 36 are effective to force the loop into the recess 22, since the slideable member moves outwardly a distance sufficient to carry the recess 22 beyond the overhanging outer end of nose 25; and when the loop 4 drops into the recess, the spring 32 then operates to retract the slideable member 12 to its innermost or locking position, as shown in Fig. 2, 55 in which position the overhanging ends of the

nose 25 prevent removal of the loop 4 from the recess 22.

The free end of the catch 21 is provided with a resilient locking finger 38 adapted to pass through the opening 6 and snap about the inwardly bent edge of top wall 5, as shown in Fig. 5. The free end of catch 21 is also provided with an up-standing nib 40 which constitutes a finger-piece by means of which the catch 21 may be pried outwardly and thus disengaged from the edge of top wall 5.

In using the clasp the catch 21 is first swung to open position and the loop 4 of the coupling 30 dropped over the catch. By simply swinging the catch to closed position, as illustrated in Fig. 4, the loop is carried into the recess 22 and automatically locked, as above explained. In order to release the loop the catch 21 is first swung to open position, and by exerting a slight outwardly and upwardly directed tension on the coupling 3, the slideable member 12 first moves outwardly, as shown in Fig. 3, and the loop then slips upwardly out of the recess and over the edges 35 of ears 18, and may then be removed from about the catch 21.

While I have shown and described one desirable embodiment of the invention, it is to be understood that this disclosure is for the purpose of illustration and that various changes in shape, proportion and arrangement of parts, as well as the substitution of equivalent elements for those herein shown and described, may be made without departing from the spirit and scope of the invention as set forth in the appended claims.

I claim:

1. A clasp comprising interconnected longitudinally slideable members, one of which is formed with a recess for receiving the loop of a coupling member and the other having a fixed part extending toward said recess and arranged to project over the entrance to said recess so as to prevent removal of said loop when the members are slid to their innermost position, resilient means associated with said members for normally holding them in said innermost position, and releasable means carried by one member and engageable with the other member for locking said members in said innermost position.

2. A clasp comprising interconnected longitudinally slideable members, one of which is formed with a recess for receiving the loop of a coupling member and the other having a fixed part extending toward said recess and so arranged that when said members are slid to their outermost position of extension, said loop may be removed from and replaced in said recess, but when said members are slid to their innermost position, said part overhangs the entrance to said recess so as to prevent removal of said loop, resilient means associated with said members for normally holding them in said innermost position, and releasable means carried by one member and engageable with the other member for locking said members in said innermost position.

3. A clasp comprising interconnected longitudinally slideable members, one of which is formed with a recess for receiving the loop of a coupling member and the other having a fixed part extending toward said recess and so arranged that when said members are slid to their outermost position of extension, said loop may be removed from and replaced in said recess, but when said members are slid to their innermost position, said part overhangs the entrance to said recess so as to prevent removal of said loop, a spring

urging said members toward and normally holding them in said innermost position, and releasable means carried by one member and engageable with the other member for locking said members in said innermost position.

4. A clasp comprising interconnected longitudinally slideable members, one of which is formed with a recess for receiving the loop of a coupling member and the other having a fixed part extending toward said recess and so arranged that when said members are slid to their outermost position of extension, said loop may be removed from and replaced in said recess, but when said members are slid to their innermost position, said part overhangs the entrance to said recess so as to prevent removal of said loop, a spring urging said members toward and normally holding them in said outermost positions, and a releasable catch pivotally mounted on one of said members and engageable with the other of said members for holding said members in said innermost position.

5. A clasp comprising interconnected longitudinally slideable members, one of which is formed with a recess for receiving the loop of a coupling member and the other having a fixed part extending toward said recess and so arranged that when said members are slid to their outermost position of extension, said loop may be removed from and replaced in said recess, but when said members are slid to their innermost position, said part overhangs the entrance to said recess so as to prevent removal of said loop, and having a cam-like surface inclined toward said recess, resilient means associated with said members for holding them in said innermost position, and releasable means for locking said members in said innermost position, said releasable means being engageable with said loop when disposed on said cam-like surface and operative when moved to locking position to act on said loop to cause said members to move to their outermost position and urge said loop into said recess, and said resilient means being effective when said loop moves into said recess to return said members to their innermost position, thereby to lock said loop within said recess.

6. A clasp comprising interconnected longitudinally slideable members, one of which is formed with a recess for receiving the loop of a coupling member and the other having a fixed part extending toward said recess and so arranged that when said members are slid to their outermost position of extension, said loop may be removed from and replaced in said recess, but when said members are slid to their innermost position, said part overhangs the entrance to said recess so as to prevent removal of said loop, and having a cam-like surface inclined toward said recess, a spring acting on said members so as normally to hold them in their innermost positions, and a releasable catch pivotally mounted on one of said members and engageable with the other of said members to hold said members in their innermost position, said catch being engageable with said loop when disposed on said cam-like surface and operative when moved to locking position to act on said loop to cause said members to move to their outermost position and urge said loop into said recess, and said spring being effective when said loop moves into said recess to return said members to their innermost position, thereby to lock said loop within said recess.

7. A clasp comprising a substantially hollow fixed member, a slideable member adapted to tele-

scope within said fixed member and having a recess between its ends adapted to receive a coupling loop, said fixed member having a part arranged to project over the entrance to said recess so as to prevent removal of said loop when said slidable member is at its innermost position, said part having a cam-like surface inclined toward said recess, a spring acting on said fixed member and said slidable member so as normally to hold the slidable member at its innermost position, and a releasable catch pivoted to the outer end of said slidable member and engageable with said

fixed member to hold said slidable member at its innermost position, said catch being engageable with said loop when disposed on said cam-like surface and operative when moved to locking position to act on said loop to cause said members to move to their outermost position and urge said loop into said recess, and said spring being effective when said loop moves into said recess to return said members to their innermost position, thereby to lock said loop within said recess.

CHARLES A. DOMLER.
